DISPENSER FOR AN OIL CAN OR THE LIKE

John C. Anderson, Hamilton, Ohio

Application July 8, 1955, Serial No. 36,874

Term of patent 14 years

(Cl. D58—17)

Fig. 1 is a side elevational view of a dispenser for an oil can or the like, showing my new design.

Fig. 2 is a rear elevational view of the device of Fig. 1.

Fig. 3 is a top plan view of Fig. 1.

The broken line showing of the can as viewed in Fig. 1 is for illustrative purposes only.

I claim:

The ornamental design for a dispenser for an oil can or the like, as shown and described.
